BUBBLER HEAD

J. Way Harlan, Phoenix, Ariz.

Application March 2, 1936, Serial No. 66,766

3 Claims. (Cl. 299—15)

This invention relates to bubbler heads such as used with drinking fountains.

Many of the bubbler heads now in use are objectionable for several reasons. For example water dripping from the mouth of the user has fallen back onto the outlet and frequently contaminated it. The outlet has usually been located where the user could press the mouth thereagainst with result that contamination has thus been transmitted. The bubbler heads have also been so formed and located that persons have been able to deflect the jets of water onto others. Injury to users has also resulted from playful "ducking" into the fountain and consequent violent contact with the outlet nozzle.

The object of the present invention is to remove the objections heretofore noted by providing a bubbler head which will throw the water jet laterally so that saliva or other secretions will not fall upon the nozzle, means being employed whereby any obstruction of the outlet will result in the diversion of the stream downwardly so that it cannot be projected onto nearby persons.

A further object is to so construct and locate the nozzle that it will be maintained clean and cannot be reached by the mouth of the user.

Another object is to provide the nozzle with a guard affording maximum protection from the mischievous practice of pushing the head of the user down toward the nozzle.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

40 In the accompanying drawing the preferred form of the invention has been shown.

In said drawing

Figure 1 is a front elevation of the bubbler head in position for use.

45 Figure 2 is a vertical section through the bubbler head on line 2—2, Figure 1.

Figure 3 is a top plan view.

Figure 4 is a bottom plan view.

Referring to the figures by characters of reference, 1 designates a sleeve having a screw threaded socket 2 whereby it can be attached to a water pipe 3 having any suitable valve 4. The upper end of the sleeve has an integral cup-like guard 5 in the form of an inverted cone a segment of which is removed as shown at 6 to pro-

vide a clearance. A rounded flange 7 is provided along the top edge of the guard while extended across the lower portion of the guard is a diametrical ridge 8 from which extend downwardly diverging draining surfaces forming the 5 bottom of the guard. One of these surfaces 9 extends backwardly and cooperates with the wall of the guard to provide a recess having a drain aperture 10 opening downwardly through said 10 wall. The other inclined surface 11 extends forwardly to the bottom of the clearance 6 and merges into an ear 12 which projects outwardly from the head and the bottom surface of which forms a shoulder 13 disposed at an angle to the 15 upper end of sleeve 1.

An outlet bore 14 opens into the socket 2 and is inclined upwardly and forwardly so as to open through and at right angles to the surface 11. The upper or outlet end of this bore is enlarged or counterbored, as at 15 and a by-pass 20 16 extends downwardly from this counterbore and opens through the shoulder 13.

It will be apparent that when valve 4 is opened a jet of water will be discharged from the nozzle formed by ear 12 and the bore therein and this 25 jet will be projected upwardly and forwardly through the clearance 6 so that the mouth of the user can be brought against the jet at a point outside of the bubbler head. The guard 5 prevents the mouth from coming against the 30 nozzle and should any saliva or other secretions drop into the head the same will be washed from the inclined surfaces, flowing off either at the drain opening 10 or over the ear 12. Thus the 35 device will be kept in a sanitary condition and danger of contamination therefrom is reduced to the minimum.

Should a finger be placed over the upper surface of the nozzle to close the water outlet, the water would not be diverted laterally as can 40 be done with most bubbler heads, but, instead the diverted water will be expelled downwardly through the by-pass 16. As the shoulder 13 extends close to the surface of the sleeve 1 it is not possible for anyone to place a finger where 45 it completely closes the by-pass.

What is claimed is:

1. A bubbler head including a member having a socket for attachment to a water supply, and a guard extending from the member and providing 50 a clearance, an inclined surface at the bottom of the guard and partly surrounded thereby, said surface being extended downwardly to the bottom of the clearance, a bore extending from the socket and inclined upwardly to and opening 55

- through said inclined surface, said bore being positioned for directing a water jet upwardly and outwardly at an incline through the clearance, and a by-pass extending from the outlet portion of said bore and opening downwardly outside of said member, said by-pass being positioned to receive and discharge liquid standing in the upper portion of the bore and matter falling into said bore.
- 10 2. A bubbler head including a socket member for attachment to a water supply, said member having downwardly diverging surfaces at its upper end, a guard carried by said member and extending above said surfaces, an inclined bore leading from the socket to one of said surfaces and positioned for directing a water jet upwardly and laterally at an incline relative to the member, the guard having a clearance for the passage of the jet, a drain opening at the lowest point of the other inclined surface, and a by-pass extending from the lower side of the outlet portion of the inclined bore and opening downwardly outside of said member, said by-pass being positioned to receive and discharge liquid standing
- 15 in the upper portion of the bore and matter falling into said bore.
3. A bubbler head including a socket member for attachment to a water supply, a flared guard on the upper end of said member, a portion of the wall of the guard being removed to provide a clearance, downwardly diverging surfaces forming the bottom of the guard and the top of the socket member, a bore in the member and inclined upwardly from the socket therein to one of the inclined surfaces to direct a water jet upwardly and outwardly at the bottom of and through the clearance, an ear projecting from the member at the bottom of the clearance and forming a continuation of said inclined surface, and a by-pass in the ear opening downwardly through the ear and outside of the member and extending upwardly to the lower side of the outlet end of the bore, said by-pass being positioned to receive and discharge liquid standing in the upper portion of the bore and matter falling into said bore.

J. WAY HARLAN.
